No. 13,431

Nov. 14, 1882

UNITED STATES PATENT OFFICE.

JOHN L. POPE, OF CLEVELAND, OHIO.

DESIGN FOR A CARRIAGE-WRENCH.

SPECIFICATION forming part of Design No. 13,431, dated November 14, 1882.

Application filed August 2, 1882. Term of patent 14 years.

To all whom it may concern:

Be it known that I, JOHN L. POPE, of Cleveland, in the county of Cuyahoga and State of Ohio, have invented and produced a new and original Design for Carriage-Wrenches, of which the following is a specification, reference being had to the accompanying engraving, forming part thereof.

My invention relates to a design for carriage-wrenches; and it consists in certain features of ornamentation, which will be hereinafter more fully described, and particularly pointed out in the claims.

In the accompanying engraving the wrench is shown as provided at one end with the usual square jaw, *a*, and at the other or handle end with three differently-sized jaws, 1 2 3. This construction of the wrench is not new, and therefore forms no part of my invention. What I have produced is a novel design of ornamentation for the shank and handle end of the wrench. The shank (or handle) *b* of the implement I have adorned on its upper side by forming a groove, *c*, which extends along the same about centrally for nearly the whole length of the wrench. I have further embellished the

wrench by beveling its upper edges on both sides of the shank and on both sides of that end of the wrench containing the multiple jaws. These beveled edges are indicated in the engraving by the letters *e e*. That portion of the body of the wrench lying between the multiple jaws I have beautified by providing a depression, *i*, oblong in shape, and curved at its extremities.

What I claim as my invention, and desire to secure by Design Letters Patent, is—

1. A carriage-wrench handle or shank ornamented with the groove *c*, substantially as shown and described.
2. A carriage-wrench having beveled edges *e e*, substantially as shown and described.
3. A carriage-wrench having the groove *c*, beveled edges *e e*, and depression *i*, substantially as shown and described.

In testimony whereof I have hereunto set my hand this 17th day of July, 1882.

JOHN L. POPE.

In presence of—

L. S. FISH,
FRANK N. WILCOX.
